CLAIM

We claim the ornamental design for a display screen or portion thereof with animated graphical user interface, as shown and described.

DESCRIPTION

FIG. 1 is a front view of a display screen or portion thereof with animated graphical user interface showing a first image.

FIG. 2 is the second image thereof.

FIG. 3 is the third image thereof.

FIG. 4 is the fourth image thereof; and, FIG. 5 is the fifth image thereof.

The appearance of the animated image sequentially transitions between the images shown in FIGS. 1-5. The process or period in which one image transitions to another forms no part of the claimed design.

The inner round-cornered vertically-oriented broken-line rectangle illustrates the perimeter of a display screen. The broken lines outside this perimeter illustrate an electronic device. The broken lines within this perimeter illustrate portions of the graphical user interface. The broken lines form no part of the claimed design.

1 Claim, 5 Drawing Sheets
